UNITED STATES PATENT OFFICE.

LOUIS H. PERLMAN, OF NEW YORK, N. Y.

DEMOUNTABLE RIM.

1,270,548.

Specification of Letters Patent. Patented June 25, 1918.

Original application filed December 4, 1916, Serial No. 135,072. Divided and this application filed February 23, 1917. Serial No. 150,485.

To all whom it may concern:

Be it known that I, LOUIS H. PERLMAN, a citizen of the United States, residing at New York, in the county of New York and State of New York, have invented certain new and useful Improvements in Demountable Rims; and I do hereby declare the following to be a full, clear, and exact description of the invention, such as will enable others skilled in the art to which it appertains to make and use the same.

This invention relates to improvements in demountable rims for automobile wheels and more particularly to the type known as transplit or cross-cut, that is, the type wherein an otherwise continuous tire carrying ring is transversely cut for enabling the ring to be relatively reduced in effective diameter for permitting the application and removal of tires having inextensible beads.

Reference to my co-pending application, Serial No. 135,072, filed December 4, 1916, of which this is a division, is made for the purpose of identification.

The object in view is the formation integrally with the rim of means constructed in such manner as to facilitate the application and removal of a rim manipulating tool.

With this and more detail objects in view, as will in part hereinafter become apparent and in part be stated, the invention comprises certain novel constructions, combinations and arrangements of parts as subsequently specified and claimed.

In the accompanying drawing:

Figure 1 is a perspective view of a rim embodying the features of the present invention.

Fig. 2 is a transverse vertical section, of a tool receiving socket, taken on the plane indicated by line 2—2 of Fig. 3.

Fig. 3 is a plan view of the tool receiving socket, a fragment of the rim being shown.

Fig. 4 is a perspective view of a rim tool detached.

Fig. 5 is a transverse section taken on the plane indicated by line 5—5 of Fig. 1, parts being seen in elevation.

Fig. 6 is a view similar to Fig. 2, showing the socket in modified form.

This invention, while directed to improvements in demountable rims, may best be un-

derstood by a detail description of the operating tool whose use is facilitated by the improved rim.

Referring to the drawing by numerals, 1 indicates an operating lever which is pivoted on a shaft 2 and has one of its ends fulcrumed on pivot 3 carried by a bifurcated post 4. The free end of the post 4 is formed cylindrically and provided with diametrically opposite outstanding locking pins 5. The shaft 2 is surrounded by sleeves 6, 6, arranged at opposite sides of the lever 1 and serving as spacers therefor. The shaft 2 is provided with a head at one end and a nut or other similar heading member at the opposite end, and between the heads of the shaft and the other ends of the sleeves 6 are arranged links 7, 7, the links being pivoted onto the shaft in a position to swing freely thereon. The free end of each link is bent substantially at right angles and is preferably tapered to form a hook 8. Each hook 8 is relatively straight, but as will become apparent serves the purpose of an ordinary hook. The links 7 are connected near their free ends by a cross rod 9 having a head at one end engaging one of the links and a nut 10 threaded onto the opposite end portion and engaging the other link. An appropriate washer may be employed between the nut and link as also between the head of rod 9 and the adjacent link.

Rim 11 is provided with a tongue 12 outstanding from one end and formed with a hook 13 adapted to enter a slot 14 formed in the opposite end of rim 11 for receiving said hook. The flanges of rim 11 at the slotted end are formed with apertures 15 for receiving the hooks 8 of links 7. The opposite end portion of the rim 11 is provided with a radially-inwardly extending projection or stud 16 which is formed integral with the rim. The stud 16 is formed with an axial recess overhung by a substantially annular flange 17, the flange being interrupted at diametrically opposite points by radial openings or slots 18. The slots 18 are disposed to be intersected by a line extending transversely of the rim and are of a size adapted to permit the passage of the pins 5, the recess in the stud 16 being proportioned to receive the cylindrical lower end portion of the bar 4. Thus stud 16 is

formed into an undercut socket with lateral notches for access of the lateral projections 5 to the undercut portion of the socket.

In operation, the rim 11 being in the non-collapsed condition seen in Fig. 1, the cylindrical portion of bar 4 is introduced into the recess in stud 16 while the lever 1 is disposed to extend in a direction transversely of the rim. The pins 5 are passed through 10 the slots 18 and then the lever 1 is swung to a position substantially alined with the rim, during which movement the pins 5 are moved beneath the overhanging flange 17. Thus the post 4 is quickly and effectively 15 anchored to the rim. The links then are caused to engage the opposite end portion of the rim by having the hooks 8 inserted in the apertures 15 and the nut 10 threaded up sufficiently for tightening the links in 20 the given position.

The stud 16, during operation of the rim on a wheel, is accommodated by a recess in the peripheral portion of the wheel body, not shown, and may serve as a driver for 25 the rim.

It is especially desirable that the locking of the post 4 to the stud 16 shall be accomplished quickly and effectively so as to prevent loss of time and obviate possibility of 30 accidental disengagement. The cylindrical portion of the post 4 is proportioned to fit snugly in the socket or bore of the stud 16, so that the post 4 may serve as a fulcrum post and without liability of objectionable 35 looseness or play.

The projecting tongue 12 may be formed in any appropriate manner, the said tongue being produced in the structure shown in the drawing by the provision of a separate

plate welded or otherwise appropriately 40 anchored to the web of the rim 11. Other shapes of tongues and other methods of connection therefor may be provided as may be desired.

It is to be noted that the rim 11 is provided 45 with a valve stem hole, as at 19, surrounded by the usual driving stud, the hole 19 being located in that end portion of the rim 11 which carries the socket provided by stud 16.

What I claim is:—

1. A transplit demountable rim having an integrally formed tool receiving socket at one end portion, the other end portion being adapted to receive part of an operating tool, the socket being formed to receive a radially 55 introduced fulcrum post and to hold said post rigidly in a radially extending position.

2. A transplit demountable rim having a radially inwardly extending stud stamped from the material of the base of the rim and 60 recessed to form an undercut socket having a notch opening into the undercut portion of the socket.

3. A transplit demountable rim having a radially inwardly extending stud recessed 65 to form an undercut socket having a notch opening into the undercut portion of the socket, and a plate fixed to the outer face of the base of the rim and extending across the socket and provided with a recess in 70 line with the main portion of the socket.

In testimony whereof I affix my signature in presence of two witnesses.

LOUIS H. PERLMAN.
